(57) **CLAIM**

The ornamental design for a combined disinfecting and sterilizing chamber as shown and described.

DESCRIPTION

2. Combined disinfecting and sterilizing chamber
Fig. 2.1 is a front, top, right side perspective view of a combined disinfecting and sterilizing chamber showing my new design;

Fig. 2.2 is a rear, top, right side perspective view thereof;
Fig. 2.3 is another rear, top, right side perspective view thereof;

Fig. 2.4 is a rear, bottom, right side perspective view thereof;
Fig. 2.5 is a right side, top, rear perspective view thereof
Fig. 2.6 is a rear, top, left side perspective view thereof;
Fig. 2.7 is a front, top, left side perspective view thereof.
